Inventor,
Clifford H. Young,
By Bakewell & Burkhardt, Atty.

UNITED STATES PATENT OFFICE.

CLIFFORD H. YOUNG, OF ST. LOUIS, MISSOURI.

DRIVING MECHANISM FOR VEHICLES.

1,279,818.

Specification of Letters Patent. Patented Sept. 24, 1918.

Application filed August 22, 1917. Serial No. 187,725.

To all whom it may concern:

Be it known that I, CLIFFORD H. YOUNG, a citizen of the United States, residing at St. Louis, Missouri, have invented a certain 5 new and useful Improvement in Driving Mechanism for Vehicles, of which the following is a full, clear, and exact description, such as will enable others skilled in the art to which it appertains to make and use the 10 same.

This invention relates to driving mechanisms for automobiles and other vehicles of the type in which power is applied directly to those wheels of the vehicle which are 15 turned to guide or change the path of travel of the vehicle.

The main object of my present invention is to provide a mechanism of the character referred to, in which the coöperating parts 20 are so constructed and designed that the mechanism will stand up successfully under rough usage.

Another object is to provide a mechanism of the character referred to that can be assembled or disassembled easily.

Still another object is to provide a mechanism of the character referred to, in which the axle housing is provided with relatively long bearings for the wheel spindles, and 30 the stub shafts or short axles to which the wheels are connected are supported at their inner ends by laterally-projecting extensions on the spindles, thus insuring an exceptionally strong and substantial structure. Other 35 objects and desirable features of my invention will be hereinafter pointed out.

Figure 1 of the drawings is a top plan view, partly in horizontal section, of a front wheel driving mechanism constructed in accordance with my invention.

Fig. 2 is a rear elevational view of said mechanism, partly in vertical section.

Fig. 3 is a vertical sectional view, taken on the line 3—3 of Fig. 2.

Fig. 4 is a perspective view of one of the wheel-carrying members.

Fig. 5 is a perspective view of one of the top members that forms part of the axle housing.

Fig. 6 is a perspective view of one of the bottom members that forms part of the axle housing.

Fig. 7 is a perspective view of one of the stub shafts or wheel axles; and

Fig. 8 is a perspective view of one of the 55 spindles.

Referring to the drawings, which illustrate the preferred form of my invention, 1 designates two drive shafts adapted to be driven by any suitable means, such, for example, as a propeller shaft, and a differential mechanism (not shown) to which the inner ends of the drive shafts 1 are connected. Each of the drive shafts 1 is provided at its outer end with a beveled pinion 65 2 that meshes with an idler 3, which, in turn, meshes with a beveled pinion 4 secured to a horizontally-disposed stub shaft or axle 5 is connected. The shafts 1 are incased in to which one of the front wheels (not shown) 70 an axle housing which preferably consists of a tubular-shaped intermediate portion 6 provided at each of its ends with a split housing portion formed by a top member A and a bottom member B, which members A 75 and B are secured to the intermediate portion 6 of the axle housing by fastening devices 7, or in any other suitable manner. At each end of the axle housing is a vertically-disposed spindle C which is journaled in 80 relatively long bearings carried by the axle housing, and the axle housing is also provided at each of its ends with an oscillating wheel carrying member D that is provided with an axle box or bearing portion in which 85 one of the stub shafts or wheel axles 5 is journaled. The wheel carrying members D are provided with angularly-disposed arms 8 to which the usual drag link (not shown) of the steering mechanism of the vehicle is 90 connected, so that when said steering mechanism is actuated the wheel carrying members D will swing horizontally and thus effect a change in the direction of travel of the vehicle. Any further description of the 95 general operation of my mechanism is not deemed necessary, as said mechanism operates in substantially the same manner as numerous other front wheel driving mechanisms which have heretofore been devised, 100 but it is constructed in a different manner from such prior mechanisms.

One distinguishing characteristic of my mechanism is that the wheel carrying members D, the spindles C and the top and bottom members A that form the split portions of the axle housing are so constructed that they are capable of successfully withstand-

ing great ~~charms~~ and loads. As shown in Figs. 5 and 6, the top and bottom members A and B each consist of a casting provided with a semi-tubular-shaped portion 9 so that when said members are combined the portions 9 will form a sleeve that surrounds the tubular-shaped member 6 that constitutes the intermediate portion of the axle housing. Said members A and B are provided with 10 segmental-shaped walls 10 whose horizontal edges butt against each other when the members A and B are assembled, the walls 10 extending throughout only a small area of the members A and B, so as to form a horizontally-disposed slot or opening in the front end of the split portion of the housing that receives an axle box 11 on one of the wheel carrying members D. The wheel carrying members D are both of the same construction and each consists of a rectangular-shaped box 11, preferably of oblong form, that is integrally connected to the inner side of a semi-circular-shaped wall or part 12 whose end portions are tied together by a 20 horizontally-disposed strap or cross piece 13 that is formed integral with same, the arm 8 previously referred to to which the drag link of the steering mechanism is connected forming an integral extension of the strap or 25 part 13. When the parts of the mechanism are assembled, as shown in Figs. 1 and 2, the axle box 11 of each of the wheel carrying members will fit snugly in the horizontally-disposed slot in the split end portion of the 30 axle housing, and the cross piece or strap 13 of said wheel carrying member will extend downwardly under the bottom member B of the axle housing, as shown clearly in Fig. 2, the curved wall 12 of the wheel carrying 35 member serving as a closure for the slot in the axle housing in which the axle box 11 on the wheel carrying member slides.

Each of the spindles C consists of a vertically-disposed pivot pin provided intermediate its ends with an enlarged integral portion 14 that serves as a thrust bearing which coöperates with relatively long, tubular-shaped bearings 15 and 16 on the top and bottom members A and B, respectively, 40 that receive the cylindrical portions 17 of said spindle that lie above and below the enlarged portion 14 of the spindle. Each of the spindles C is provided at its lower end with a non-circular-shaped portion 18 that 45 fits in a non-circular-shaped hole 19 in the cross piece 13 of the wheel carrying member D with which said spindle coöperates, the wheel carrying member being securely connected to said spindle by means of a nut 19 mounted on the lower end of same beneath 50 the cross piece 13 of the wheel carrying member, as shown in Fig. 2.

Each of the stub shafts or wheel axles 5 is provided with a portion 20 that fits in a 55 roller bearing or other friction-reducing

bearing 21 mounted in the axle box 11 on its coöperating wheel carrying member, and each of said wheel axles is also provided on its inner end with a sleeve or tubular portion 22 that surrounds a roller bearing or other 70 suitable friction-reducing bearing 23 which receives a laterally-projecting extension 24 on the spindle C with which said wheel axle coöperates, said extension 24 preferably being formed integral with the enlarged portion 14 of the spindle.

The horizontal surfaces on the top and bottom members A and B of the axle housing that form the upper and lower edges of the horizontal slot in the axle housing in 80 which the axle boxes 11 on the members D slide are preferably provided with ball races 25, as shown in Figs. 5 and 6, that receive ball bearings 26, shown in Fig. 2, the upper and lower edges of the axle boxes 11 also being provided with ball races 25. I also prefer to arrange ball bearings 27 between the thrust bearings 15 and 16 on the axle housing in which the spindles are journaled, and if desired, ball bearings 28 can be arranged 85 between the top members A of the axle housing and the idlers 3 that form part of the driving mechanism, the idlers 3 being rotatably mounted on the bearings 15. The top members A of the axle housing are preferably so designed that they lap over the edges of the curved walls 12 of the wheel carrying members, and if desired, ball bearings 29 can be arranged in ball races formed in the upper edges of said curved walls 12 and in the 90 overlapping portions of the top members A, so as to further reduce the friction between said parts. As shown in Figs. 5 and 6, the semi-tubular portions 9 of the members A and B are provided on their inner sides with 95 ribs 30 that form abutments for roller bearings 31 in which the drive axles 1 are journaled, and if desired, the wheel axles or stub shafts 5 can be provided with collars 32, as shown in Fig. 2, that bear against the curved 100 walls 12 of the wheel carrying members in which said wheel axles are journaled.

A front axle driving mechanism of the construction above described is exceptionally strong and rigid, owing to the fact that each 115 of the spindles of same is provided intermediate its ends with an integral thrust bearing 14 that is arranged between two relatively long bearings on the axle housing that surround the upper and lower end portions of the spindles, the strain to which the spindles are subjected when the mechanism is in use being partly relieved by the relatively large coöperating bearing surfaces on the axle boxes 11 of the wheel carrying members and the portions of the axle housing on which said boxes slide. In addition to the fact that the spindles are firmly braced and held securely in position by a 120 number of coöperating thrust bearings, the 125 130

wheel axles or stub shafts 5 of my improved mechanism are also exceptionally strong, owing to the fact that each of said shafts is journaled intermediate its ends in a relatively large anti-friction bearing carried by its coöperating wheel carrying member, and its inner end is supported by a lateral extension 24 on the spindle with which it coöperates. The parts of my improved mechanism can be assembled or disassembled easily, owing to the novel construction of same, and as the principal parts of same which move relatively to each other are equipped with ball bearings or other suitable anti-friction bearings, the wheels of the vehicle can be turned easily to change the direction of travel of the vehicle. The mechanism can be used for a long period in view of the fact that there are very few rubbing parts on same which are apt to wear out quickly. While I have herein illustrated my improved driving mechanism applied to the front wheels of a vehicle, it will be obvious that it could be applied to the rear wheels of a vehicle of the type in which the rear wheels are adapted to be turned so as to control or assist in controlling the direction of travel of the vehicle.

Having thus described my invention, what I claim, and desire to secure by Letters Patent, is:

1. A driving mechanism for vehicles, comprising a supporting structure, a vertically-disposed spindle journaled in same and provided intermediate its ends with an enlarged portion, relatively long, tubular-shaped bearings on said supporting structure that surround said spindle and coöperate with the enlarged portion on said spindle to form a thrust bearing, a laterally-projecting extension on the enlarged portion of said spindle, and a horizontally disposed wheel axle provided at its inner end with a tubular portion into which said extension projects.

2. A driving mechanism for vehicles, comprising an axle housing provided at one end with a split portion provided with a top member and a bottom member, relatively long, tubular-shaped bearings integrally connected to said members and projecting toward each other, a vertically-disposed spindle journaled in said bearings and having an enlarged portion that is interposed between the inner ends of said bearings, an extension projecting laterally from the enlarged portion of said spindle, a horizontally-disposed wheel axle provided at its inner end with a tubular portion, and a bearing in the tubular portion of said axle that receives the lateral extension on said spindle.

3. A driving mechanism for vehicles, comprising an axle housing provided at one end with a supporting structure equipped with a horizontally-disposed slot, a vertically-disposed spindle journaled in said support-

ing structure, a wheel carrying member having a curved wall that serves as a closure for said slot and which is provided on its inner side with an axle box that projects into said slot and slides on the lower edge of same, a cross piece or strap integrally connected to the curved wall of said wheel-carrying member and projecting underneath said supporting structure, a wheel axle journaled in said axle box, and means for securing the cross piece of said wheel carrying member to the lower end of said spindle.

4. A driving mechanism for vehicles, comprising an axle housing provided with a split end portion formed by a top member and a bottom member having segmental-shaped walls that contact with each other, an oscillating wheel carrying member having an axle box that slides horizontally in a slot formed in the split end portion of the axle housing, a vertically-disposed spindle journaled in bearings on said top and bottom member and provided with an enlarged portion that is interposed between said bearings, and a wheel axle journaled in said axle box and provided at its inner end with a hollow portion that receives a laterally-projecting extension on said spindle.

5. A driving mechanism for vehicles, comprising a supporting structure provided with a horizontally-disposed slot, a vertically-disposed spindle journaled in said structure, an oscillating wheel carrying member provided with a curved wall that serves as a closure for said slot, an axle box on said wall that projects into said slot, a cross piece on said wheel carrying member arranged under said supporting structure and connected to said spindle, and anti-friction bearings arranged between said axle box and the edges of said slot and between the upper edge of the curved wall of said wheel carrying member and a portion on said supporting structure that laps over same.

6. A driving mechanism for vehicles, comprising an axle housing composed of a tubular-shaped intermediate member and a split end portion formed by top and bottom members secured to one end portion of said intermediate member so as to form horizontally divided housing, tubular-shaped bearings on said top and bottom members arranged in vertical alinement with each other and having their inner ends spaced apart, a vertically-disposed spindle journaled in said bearings and provided with an enlarged portion that lies intermediate said bearings, anti-friction bearings arranged between said enlarged portion and the bearings above and below same, an oscillating wheel carrying member provided with an axle box that slides in a horizontally-disposed slot in the split end portion of the housing, an integral cross piece on said wheel carrying member

secured to said spindle, a wheel axle journaled in the axle box in said wheel carrying member, and a connection between said spindle and the inner end of said wheel 5 axle.

7. A driving mechanism for vehicles, comprising an axle housing provided with a split end portion formed by a top member and a bottom member that have coöperating 10 openings in same which form a horizontally-disposed slot, a vertically-disposed spindle journaled in bearings on said top and bottom members and provided with an enlarged portion that lies intermediate said bearings,

an oscillating wheel carrying member having an axle box that is slidingly mounted in said slot, said wheel carrying member having a curved portion that serves as a closure for said slot and a cross piece integrally connected to said curved portion and secured to said spindle so as to cause the wheel carrying member to oscillate when the spindle turns, and a wheel axle journaled in said axle box and provided at its inner end with a friction reducing bearing that receives a laterally-projecting extension on the enlarged portion of said spindle. 15 20 25

CLIFFORD H. YOUNG.

Corrections in Letters Patent No. 1,279,818.

It is hereby certified that in Letters Patent No. 1,279,818, granted September 24, 1918, upon the application of Clifford H. Young, of St. Louis, Missouri, for an improvement in "Driving Mechanism for Vehicles," errors appear in the printed specification requiring correction as follows: Page 1, after line 68, insert the words *to which one of the front wheels (not shown)*; same page strike out line 70 as now numbered; and that the said Letters Patent should be read with these corrections therein that the same may conform to the record of the case in the Patent Office.

Signed and sealed this 19th day of August, A. D., 1919.

[SEAL.]

J. T. NEWTON,

Commissioner of Patents.
